ISAAC B. ABRAHAM, OF CHICAGO, ILLINOIS.

WEDGE-SUPPORTING BLOCK FOR AXLE-BOXES.

1,133,082.

Specification of Letters Patent. Patented Mar. 23, 1915

Application filed March 30, 1914. Serial No. 328,417.

To all whom it may concern:

Be it known that I, ISAAC B. ABRAHAM, a citizen of the United States, residing at Chicago, in the county of Cook and State of Illinois, have invented certain new and useful Improvements in Wedge-Supporting Blocks for Axle-Boxes, of which the following is a specification.

This invention relates to the improvement of the driving boxes of locomotives, and particularly to the provision of means for supporting the wedge of the driving or axle box against settlement due to vibration and stresses.

The lines of construction of locomotive driving or axle boxes have been fixed or standardized, as a result of extensive experience. But though the principles of construction for such boxes have been given exhaustive consideration, and have been subjected to endless calculation, the records of the railroads show that the readjustments occurring in the driving or axle boxes while in actual every day use, results in serious accidents to the mechanism, and not infrequently results in serious accidents to persons carried by the locomotive or its train of cars.

The driving or axle boxes are built in the pedestal legs which are rigidly or integrally connected to an upper and lower frame brace. Against one of the legs a shoe, sometimes termed a wedge, but not having the form or function of a wedge, is disposed; while against the opposite leg a wedge, in form and function, is disposed. The wedge is provided to take up wear due to the vertical sliding movement of the axle box, and to protect the pedestal leg from wear. The wedge is adjusted to take up wear by means of a screw which projects vertically above the pedestal cap or binder, and which is held in position by nuts which are threaded against the upper and lower faces of the pedestal cap or binder. Frequent oiling of the driving or axle box is required, and the effect of this oil is to lubricate the wedge adjusting screw, which works loose and against which the wedge vibrates and even pounds.

I have found, as a result of close shop study of locomotives and the conditions of practical service, that the present means of supporting the wedges of locomotive driving boxes results in the following:

1. The sides of the jaw, or the pedestal

legs, are broken at their point of connection with the frame brace. 2. The axle or driving box wears oblong or convex and the wedge wears concave, thus causing a rocking. 3. The increased vibration and pounding results in the breaking of the connecting rod near the pin. 4. It also results in the snapping of the driver pin. 5. It also causes the driver to break near the axle. 6. It also causes the wheel to climb the rail and to ditch the locomotive. Each of the above effects may be followed by small or great injury to the locomotive, and small or great injury or loss of life.

To remedy the present conditions without requiring any material variation from the present practice, and without requiring the alteration of the lines of construction of the parts of the driving or axle boxes, is the leading object of my present invention.

Another object of the invention is to provide means for supporting the wedge which is adapted to be adjusted, so as to give a positive support to the wedge and to take up wear.

A still further object of the invention is the provision of improved means for supporting the wedge, which will have a positive, biting contact with the wedge and with the pedestal cap or binder.

With the above and other objects in view the invention comprises certain new and useful constructions, combinations and arrangements of parts, clearly described in the following specification and fully illustrated in the accompanying drawings, in which:

Figure 1 is a side elevation showing the accepted manner of constructing the jaw and of securing the shoe and wedge in position. Fig. 2 is a cross sectional view showing the improved means for supporting the wedge against play and to prevent readjustments when once secured in position. Fig. 3 is a detail perspective view showing the modified form of the invention, provided to render a single device adjustable to meet the conditions caused by the elevation of the wedge to take up wear.

Referring to the accompanying drawings illustrating the practical embodiment of the invention 5 designates upper frame brace and 6 the lower frame brace. The pedestal legs 7 and 8 are rigidly or integrally connected to the respective upper and lower frame braces. The pedestal cap or binder 9

is secured at its ends to the lower brace 6 by means of the usual bolts 10. Against the pedestal leg 7 the usual shoe 11, sometimes termed a wedge, but not having either the form or function of a wedge, is secured. The wedge 12 is disposed against the pedestal leg 8. This wedge 12 is adjusted to take up wear by means of the adjusting screw or screws 13, which extends vertically 10 through the pedestal cap or the binder, and which is held in position by the nut 13', which is threaded against the upper side of the cap or binder, and by the nut 13'', which is threaded against the lower side of the 15 binder.

In the usual condition of affairs the wedge 12 is supported by the screw 13, and this screw is subjected to all the vibrations which are developed in the wedge. The 20 pressure of the wedge against the screw, which engages the wedge in such a manner as to induce a rocking action, when the wedge has worn to some extent, promotes the play of the driving or axle box, and hastens 25 the accidents to machine and man which follows from excessive play and vibration. The pedestal legs or the jaw of the driving box have been broken away from the engine frame; the connecting rod has been broken 30 away from the pin; the driver pin has been snapped off; the driver has been broken near the axle; the box has been worn convex and the wedge and the shoe have been worn concave, or dished through wear; and 35 the practical result of these readjustments and changes is to disable the locomotive, and to even lead to its jumping the rail, under the impulses and rocking action developed 40 through the vibrations and pounding resulting from the pressure of the wedge against its adjusting screw and the increase of play of the wedge, and axle box.

The present invention was designed to 45 overcome the defects inherent in the present practice, without requiring that the accepted lines of construction be altered.

In carrying out my invention I provide a 50 solid block 14, made of hard, highly tempered, metal, such as high grade steel. This block is substantially rectangular, and is 55 large enough to neatly fit between the wedge screws. The vertical sides of the block 14 are formed smooth, but the upper and lower sides are provided with a series of relative sharp teeth, which are adapted to have a biting contact with the wedge and with the pedestal cap or binder. The teeth 14' are formed by cutting the block and are tempered so as to be considerably harder than 60 the metal of the wedge or the pedestal cap.

After the wedge has been adjusted to the desired position a block 14 of a width just sufficient to snugly fit between the wedge and the pedestal cap or binder is positioned on 65 the binder or cap. The pressure of the

wedge upon the teeth of the block 14 and the pressure transmitted through the block to the lower teeth will cause a biting engagement of the teeth of the block with the wedge and the binder, so that the block will 70 not be displaced.

As the block is made of very hard metal it will effectively resist all compression and vibration strains, and will positively support the wedge against all downward play, 75 regardless of the screw or screws employed for this purpose.

A number of blocks may be provided, each differing from the other by a slight gradual increase in width or height, so that when a 80 given block becomes useless, owing to the elevation of the wedge to take up wear, another block, slightly higher can be used, which will be sufficiently high to safely support the wedge. To accomplish this end I 85 have also devised a sectional block, comprising a lower block section 15, which has teeth 15' on its lower side for biting engagement with the member which it is placed against, and which is provided with up- 90 standing pins 15'', spaced apart from each other. A second block section 16 is provided, which is formed with teeth 16' on its upper side for biting engagement with the element it is placed in contact with. This 95 block section 16 is formed with sockets or spaced openings 16'' adapted to receive the pins or studs 15'' of the block section 15. By the interfitting engagement of the pins or studs 15'' with the openings or sockets in 100 the block section 16 the two block sections are securely united to form a solid block.

In order to increase the height of the sectional block I provide a series of shims 17, which are adapted to match the inner faces 105 of the block sections and are formed with openings 17' through which the pins or studs 15'' may be inserted, whereby the shims may be locked between the block sections. When it is desired to increase the 110 height of the sectional block one or more of the shims, which are relatively thin and of hard metal, are placed between the block sections and the sections are locked to each other by interfitting engagement of the pins 115 and the sockets.

It is apparent that teeth may be provided on only one side of the block, and that any means having an equivalent interlocking action may be substituted for the teeth. It 120 is understood that any block or other device intended to do the work of my improved block, which I term a "dead block" is comprehended by the invention, as defined in the following claims.

Having described my invention I claim:

1. The combination with an axle box for locomotives having a binder and a wear adjusting wedge against which the box slides; of a solid block located under the wedge and 130

- on the binder and supporting the wedge against rocking and downward movement.
2. The combination with a locomotive axle box having a binder and a wear adjusting wedge and a screw for adjusting the relation of the wedge to the axle box; of a solid block located on the binder adjacent the screw and supporting the wedge against downward movement.
- 10 3. The combination with a locomotive axle box having a wear adjusting wedge and a binder; of a block seated on the binder and supporting the wedge and having biting contact with the wedge.
- 15 4. The combination with a locomotive axle box having a wear adjusting wedge and a binder; of a block seated on the binder and supporting the wedge and having biting contact with the binder.
- 20 5. The combination with a locomotive axle box having a wear adjusting wedge and a binder; of a block seated on the binder and supporting the wedge and having biting contact with the binder and the wedge.
- 25 6. The combination with a locomotive axle box having a wear adjusting wedge and a binder; of a block seated on the binder and having teeth adapted to have biting contact with the wedge to support the wedge against play.
- 30 7. The combination with a locomotive axle box having a wear adjusting wedge and a binder; of a block seated on the binder and having interlocking engagement with the binder and arranged to support the wedge.
- 35 8. The combination with a locomotive axle box having a binder and a wear adjusting wedge; of a block having interlocking engagement with the wedge and supported on the binder to hold the wedge elevated.
- 40 9. The combination with a locomotive axle box having a binder and a wear adjusting wedge; of a block having interlocking engagement with the binder and the wedge and supporting the wedge in elevated position.
- 45 10. In axle box constructions, a wedge supporting block having teeth on one side thereof.
- 50 11. In axle box constructions, a wedge supporting block having teeth on opposite sides thereof.
- 55 12. In axle box constructions, a wedge supporting block having means on one side thereof to interlock with the wedge.
- 60 13. In axle box constructions, a wedge supporting block having means on the opposite sides thereof adapted to form a biting interlock.
- 65 14. In axle box constructions, a sectional block for supporting the wedge and means detachable between the sections for increasing the height of the block.
- 70 15. In axle box constructions, a sectional block for supporting the wedge, means insertible between the sections of the block for increasing the height of the block, and means on the opposite sides of the block adapted to form an interlock.
- 75 16. In axle box constructions, a block for supporting the wedge consisting of interlocking sections and a shim adapted to be interlocked between the sections.
- 80 17. In axle box constructions, a block for supporting the wedge consisting of companion sections, each of said sections having teeth on one side thereof to form a biting contact, one of said sections having pins thereon and the other section having openings to receive the pins.
- 85 18. In an axle box construction, a block for supporting the wedge consisting of companion sections, each of said sections having teeth on one side thereof to form a biting contact, one of said sections having means to fit into the other section, and a shim insertible between the sections.
- 90 19. In an axle box construction, a block for supporting the wedge consisting of companion sections adapted to interlock with each other, each of said sections having teeth on one side thereof adapted to have a biting contact, and a shim insertible between the sections for varying the height of the block.
- 95 20. The combination with an axle box including a binder and a wear adjusting wedge; of a support for the wedge having parallel upper and lower surfaces and adapted to hold the wedge in its normal adjusted position.
- 100 21. The combination with an axle box including a binder and a wear adjusting wedge and means for adjusting the wedge; of a solid support located between the binder and the wedge and adapted to hold the wedge in its adjusted position against the loosening of the adjusting means.
- 105 22. The combination with an axle box including a stationary member and a wear adjusting wedge and means for adjusting the wedge; of a sectional support located on the stationary member and supporting the wedge and adapted to be increased in vertical thickness to form a non-compressible and non-shrinkable support for the wedge.
- 110 120 In testimony whereof I affix my signature in presence of two witnesses.
